UNITED STATES PATENT OFFICE

2,448,774

SEWING MACHINE

Martin L. Cook, Chicago, Ill., assignor to Union Special Machine Company, Chicago, Ill., a corporation of Illinois

Application December 28, 1946, Serial No. 719,059

13 Claims. (Cl. 112—18)

1

This invention relates to cup feed sewing machines and more particularly to puller means applied to such machines to assist in feeding the work and retaining it in proper relation to the feed cups.

A primary object of the invention has been to provide puller means arranged to cooperate with one of the feed cups, at a point beyond the point of stitch formation, for advancing the work away from the bight of the feed cups and adapted to be shifted under foot or knee control into an inactive position to facilitate the adjustment of the work or the introduction of a new piece of work.

Another object of the invention has been to achieve the foregoing purpose in a simple inexpensive and effective manner, with only a few parts.

A further object of the invention has been to provide for the automatic throwing out of the puller means upon the separation of the feed cups under foot, or knee, or manual control.

A still further object of the invention has been to provide a puller mechanism of the above indicated character which may be readily applied to existing cup feed machines without the necessity of modifying their present construction. This has, in fact, been accomplished without the necessity of drilling new holes or performing other machining operations on the frame of the existing basic machine selected for the illustrative embodiment of the invention.

In the preferred embodiment of the invention the arrangement is such that as one of the feed cups is shifted away from the other, by the operation of a foot treadle or the like, to enable the adjustment of the work or the insertion of a new piece of work between the cups, the puller means is also shifted away from its associated feed cup to further facilitate the handling of the work. More space is thus provided in the region of the feed cups for the manipulation of the work by the fingers of the operator.

Other objects, features, and advantages of the invention will appear from a detailed description of several illustrative forms of the same which will now be given in conjunction with the accompanying drawings, in which:

Figure 1 is a view, partly in rear elevation and partly in vertical section, of a machine embodying the present invention, a supporting table therefor being also indicated in section;

Figure 2 is a detail view in elevation of an overhanging arm portion of the machine;

Figure 3 is an end elevation of the machine, as viewed from the right in Figure 1, certain parts being broken away to illustrate the construction more clearly;

Figure 4 is an enlarged horizontal section taken along the line 4—4 of Figure 1, the puller means

2

being shown in its active position in full lines and in its inactive position in broken lines;

Figure 5 is a detail view in section along the line 5—5 of Figure 4;

Figure 6 is a sectional view, taken along the line 6—6 of Figure 4, showing the puller means in side elevation;

Figure 7 is a detail view, in plan, of a portion of the frame of the machine with the top cover removed;

Figure 8 is a rear elevational view of a portion of a machine similar to the one illustrated in Figure 1 but showing a modified puller construction;

Figure 9 is a horizontal sectional view taken along the line 9—9 of Figure 8;

Figure 10 is a detail view of a fragmentary portion of the machine, as viewed from the right end of Figure 8, showing the modified arrangement for supporting and operating the puller means; and

Figure 11 is a detail view in elevation of a portion of a further modified form of puller means.

The machine illustrated in connection with both embodiments of the invention is of the general type disclosed in the Hacklander Patent No. 2,043,749, granted June 9, 1936. It comprises a main frame 10 arranged to support the various operating mechanisms and to house and to provide automatic lubrication for a portion of these mechanisms. This main frame includes a vertical standard portion arranged to be supported in any suitable way, as by resting upon the surface of a work table, such as indicated at 11 in Figure 1. At the top of the vertical standard the frame has a laterally extending overhanging arm 12. A main operating shaft 13 is provided horizontally within the vertical standard and is preferably provided with a combined handwheel and pulley 14 at each end, exterior of the frame.

Power may be supplied to either of the pulleys 14 by means of a belt 15 adapted for connection in a conventional manner with any suitable source of power, such as an electric transmitter (not shown) mounted beneath the table 11. The work, such as hosiery, or the like, intended to be stitched upon the operation of the machine and given an overedge type of seam, is fed through the stitch forming zone by means of a pair of feed cups 16 and 17. These are secured by set screws or the like to the lower ends of shafts 18 and 19 depending from the overhanging arm 12 of the frame. The stitch forming devices include a

horizontally reciprocable needle 20 and a pair of loopers 21 and 22, all arranged to be given their stitch forming movements by mechanism, of the type disclosed in said Hacklander patent, driven from the main shaft 13. A suitable uncurler 23, of conventional construction, may be provided for

assisting in directing the work correctly into the path of the feed cups.

The shaft 19 for the outer feed cup is journalled within a sleeve 24 carried by a clamping member or retainer 25 which is pivotally supported in the overhanging arm 12 by means of a stud 26. Secured to this stud is a bell-crank lever 27 the free end of a horizontally disposed arm of which is engaged by a compression spring 28. The opposite end of the spring abuts against an adjustable C-frame 29 which is carried at the upper end of a threaded sleeve 30 cooperating with a threaded opening in a lug extending outwardly from the frame 10. The sleeve may be adjusted to any desired position by turning a knurled head 31 at its lower end and may be locked in adjusted position by a knurled nut 32. Spring 28 surrounds and is retained by the upper portion of a rod 33 which passes upwardly through the sleeve 30 and is provided adjacent its upper end with an elongated opening 33a that receives a reduced portion at the end of the horizontal arm of the lever 27. Secured to the rod 33 between the arms of the C-frame 29 is a collar 34. A spring 34a acting at one end against this collar and at the other end against the lower arm of the C-frame serves to urge the rod into a position in which the collar 34 engages the upper arm of the C-frame. At this time the upper edge of the opening 33a has a slight clearance with respect to the end of the lever 27 so that the latter is freely rocked by the spring 28 into its extreme clockwise position (Figure 1). Rod 33 may be moved downwardly in opposition to spring 34a by suitable connections including a chain 35 connected with the lower end of the rod and arranged to be operated by a treadle or knee-controlled member or the like (not shown). The limit of movement of the lever 27 in response to the action of spring 28 is determined by the engagement of the upper end 36 of an upwardly extending arm of the lever with the face of an eccentric 37. The latter is rotatably mounted in the overhanging arm and is arranged to be turned by means of a stud 38 having a slotted head accessible from the exterior of the frame. A similar eccentric 39 adjustable exteriorly of the frame by means of a headed stud 40 serves to determine the limit of movement of the lever 27 in the opposite direction. Such movement may be brought about by grasping the outer cup 17 and swinging it outwardly or, as is customary in the operation of machines of this type, it may be brought about by the downward movement of the rod 33, in opposition to the spring 34a, by means of the treadle or knee-controlled chain 35.

A plate-like puller member 41, having a bent-over ear 41a, is secured through the latter, by means of a screw 42, to a lever 43. The latter is pivotally mounted, by means of a large headed screw 44, upon a bracket 45. This bracket projects horizontally from the forward face of the vertical standard and has a vertically extending portion 46 which is secured to the standard by means of a pair of screws 47. Lever 43 has a rearwardly extending arm 48 provided in one edge with a series of notches 49 arranged to receive the hooked end of a tension spring 50. At its opposite end this spring is secured to a screw or stud 51 carried by the bracket 45. This arrangement is such that the spring 50 normally rocks the lever 43 into the position indicated in full lines in Figure 4. The tension of the spring 50 may be varied to a certain extent by selection of an appropriate one of the notches 49.

Puller member 41 serves to urge the work yieldingly against the periphery of the outer feed cup 17 and thus assists in the feeding of the work. It constitutes, in effect, an auxiliary feed beyond the point of stitch formation and thus exerts a puller action upon the work. The outer end of the puller member is preferably formed with a deep notch or slot across which extends a cutting edge 52a provided on a separate flat blade 52 which may suitably be retained against one face of the puller member by overturned tabs 53 and 54. This arrangement is such that a guarded cutting edge, disposed in a vertical plane and inclined toward the operator from the vertical, is provided closely adjacent to the point of stitch formation. It enables the chains of stitching between successive articles to be severed with a simple movement of the hand and with a minimum wastage of thread. The opposite end of the puller member is preferably provided with a curved portion 55 which extends beneath the inner feed cup 16 and a similar but shorter tail or projection 56 which extends over the upper edge of the rim of the feed cup 16. These portions of the puller member assist in guiding the work properly into the path of the feed cup 17 at the point where it is engaged by the puller member. Jamming of the work between the periphery of feed cup 16 and the inner edge of the puller member is effectively prevented.

Provision is made for the automatic swinging of the lever or arm 43 against the action of the spring 50 to carry the puller member from the full line to the dotted line position indicated in Figure 4. For this purpose a screw 57 is carried by the lever and extends downwardly therefrom. It is locked in place by means of a lock nut 58. A chain 59 or other flexible connection is provided between the chain 35 and the screw 57. At its upper end chain 59 is connected by a small wire clip 60 directly with the screw 57, while at its lower end it is correspondingly connected with the chain 35 by means of a wire clip 62. To guide the chain 59 and retain it in a position in which it will not interfere with the movement or manipulation of the work, a tubular retainer 61 is provided. This may suitably have the configuration indicated in Figures 1, 3, and 4, the end of the tube being bent and directed toward screw 57. It may be supported in any suitable way, as by welding or otherwise securing it to the lower edge of the bracket 45. As will be seen, the arrangement is such that a downward movement of the chain 35, under control of the treadle or knee-operated member, will cause downward movement of the chain 59 so that the upper end of the latter will pull the screw 57 toward the mouth of the tube and swing the lever 43 in the manner indicated. The arrangement is preferably such that a slight amount of slack is provided in the chain 59 so as not to interfere with the action of the spring 50 in holding the puller member against the periphery of the cup 17.

Referring now to Figures 8, 9, and 10, a modified arrangement of the puller member is disclosed. The sewing machine may suitably be of the same construction as in the first embodiment. However, the puller member, in lieu of being supported directly from the frame of the machine, is supported indirectly from the frame through the aid of the bearing sleeve for the outer cup shaft. Thus, a plate 65 may be secured to a laterally extending flange 66 at the lower end of a bearing sleeve 67 for the shaft of the outer cup. The plate may be secured to the flange by means

of screws 68. A pivot stud 69 is threaded into the plate 65 and is adapted to receive a hub portion 70 of a lever 71. As shown in Figure 8, the hub 70 may be in the form of a flanged sleeve secured to the under surface of the lever 71 by welding or the like. A spring 72, which surrounds the hub 70, has one end engaged with a suitable opening (not shown) in the plate 65 and its other end engaged in one of a series of small openings 73 extending through the lever 71. By proper selection of the opening 73 to receive the end of the spring, the tension of the latter may be properly adjusted so that the lever 71 will be urged in a clockwise direction (Figure 9) under the desired force. Spring 72 also serves to retain the lever 71 against the under surface of the head of the screw 69.

At its outer end there is mounted on the lever 71, by means of a screw 74, a puller member 75 similar in most respects to the puller member 41. The principal difference between the two members is in the manner of securing them to the swingable arm. Puller member 75 has an over-turned portion 76 at its top which rests upon the upper surface of the arm 71 and is secured thereto by the screw 74. It will be noted that in both embodiments, the angular position of the puller member in relation to the supporting arm or lever may be varied, as desired, by loosening the retaining screw and then tightening it when the member has been properly adjusted.

At the opposite side of the pivot stud 69 the lever 71 is provided with a lateral extension 77 which is bent upwardly for a suitable distance to provide an arm 78 to which is pivotally connected, by means of a screw 79, an eye or other fitting at the end of a flexible cable 80. Cable 80 is passed through a bent tube 81 secured to the front face of the machine frame by means of a bracket 82 held by a pair of screws 83. At its lower end, below the tube 81, the cable is connected with the chain 35 which, as in the first embodiment, is connected with a foot treadle or knee-control or the like and serves to swing the outer cup away from the inner cup. The arrangement of the tube 81 and the cable 80, as well as the upwardly extending arm 78 of the lever 71, is such as to avoid interference with the movement and manipulation of the work and to position the end of the cable for a proper pull on the arm. As in the first embodiment, the spring 72 normally serves to hold the puller member 75 against the periphery of the outer cup but upon downward movement of the chain 35, the lever 71 is swung outwardly into the position indicated in Figure 9, or even beyond, if desired, to provide free access to the region of the feed cups for introduction or adjustment of the work. This automatic outward movement of the puller member is brought about as an incident to the movement of the outer cup away from the inner feed cup. The arrangement is also such that the puller member may be swung outwardly by hand, independently of the operation of the treadle and the outward movement of the feed cup. The flexible cable 80 permits such movement of the puller member in the same manner as the flexible chain 59 of the first embodiment.

In Figure 11 there is shown a slight modification of the second form of the invention. Here, the arm 78a extending upwardly from the lever 71a has its upper end bent over to provide a horizontally extending ear 84 to which the end of cable 80a is connected by screw 79a.

While several illustrative embodiments of the

invention have been described in considerable detail, it will be understood that numerous changes in the construction and arrangement of the various parts may be made without departing from the general principles and scope of the invention.

What I claim is:

1. In a cup feed sewing machine having a main frame, a pair of feed cups adapted to engage and feed the work, a shaft connected with each of said cups for driving the same, one of said shafts having its axis in fixed relation to said frame and the other of said shafts having its axis shiftable in relation to the frame to separate the feed cups, a puller member arranged to cooperate with one of said feed cups, means carried by said frame for shiftably supporting said puller member, and treadle operated means for shifting the axis of said other of said shafts and concurrently shifting said puller member away from said one of said feed cups.
2. In a cup feed sewing machine having a main frame, a pair of feed cups adapted to engage and feed the work, means for supporting and driving said feed cups, means for yieldingly urging said cups together, said cups being separable to permit the introduction of work therebetween, a shiftable puller member urged yieldingly against the periphery of one of said feed cups, and means operable at will for concurrently separating said feed cups and shifting said puller member away from said one of said cups.
3. In a cup feed sewing machine having a main frame, a pair of feed cups adapted to engage and feed the work, means for supporting and driving said feed cups, means for yieldingly urging said cups together, said cups being separable to permit the introduction of work therebetween, a shiftable puller member urged yieldingly against the periphery of one of said feed cups, and treadle operated means operable at will for concurrently separating said feed cups and shifting said puller member away from said one of said cups, said treadle operated means including flexible connections to one of said feed cups and to said puller member.
4. In a cup feed sewing machine having a main frame, a pair of feed cups adapted to engage and feed the work, means for supporting and driving said feed cups, means for yieldingly urging said cups together, said cups being separable to permit the introduction of work therebetween, a shiftable puller member urged yieldingly against the periphery of one of said feed cups, an arm pivotally carried by said frame for supporting said puller member, and means including a flexible connecting member operable at will for moving said arm about its pivot to carry said puller member away from said one of said feed cups.
5. In a cup feed sewing machine having a main frame, a pair of feed cups adapted to engage and feed the work, means for supporting and driving said feed cups, means for yieldingly urging said cups together, said cups being separable to permit the introduction of work therebetween, a shiftable puller member urged yieldingly against the periphery of one of said feed cups, an arm pivotally carried by said frame for supporting said puller member, and treadle operated means including a flexible connecting member for moving said arm about its pivot to carry said puller member away from said one of said feed cups, said connecting member enabling manual shifting of said arm to carry said puller member to an inactive position.

6. In a cup feed sewing machine having a main frame, a pair of feed cups adapted to engage and feed the work, means for supporting and driving said feed cups, means for yieldingly urging said cups together, said cups being separable to permit the introduction of work therebetween, a shiftable puller member urged yieldingly against the periphery of one of said feed cups, treadle operated means for separating said feed cups, and a flexible connection from said treadle operated means to said puller member for shifting the latter away from said one of said feed cups.

7. In a cup feed sewing machine having a frame, a pair of normally parallel shafts carried by said frame in inner and outer relation, a feed cup at the end of each shaft, spring means for normally urging the peripheries of said cups into engagement, one of said shafts being pivotally supported and arranged to have its axis tilted to carry its feed cup away from the other, a puller member cooperating with the cup of said one shaft, a spring-urged, pivotally mounted arm carrying said puller member, and treadle operated means for rocking said pivotally supported shaft and said arm to separate said cups and to carry said puller member away from the associated cup.

8. In a cup feed sewing machine having a frame, a pair of normally parallel shafts carried by said frame in inner and outer relation, a feed cup at the end of each shaft, spring means for normally urging the peripheries of said cups into engagement, the outer of said shafts being pivotally supported and arranged to have its axis tilted to carry its feed cup away from the other, a puller member cooperating with the cup of the outer shaft, a spring urged arm pivotally mounted within said outer cup, said arm carrying said puller member, treadle operated means connected with said outer shaft for rocking the same to carry the associated cup away from the other cup, and means connecting said treadle operated means with said arm to shift said puller member away from the cup of said outer shaft.

9. In a cup feed sewing machine having a frame, a pair of normally parallel shafts carried by said frame in inner and outer relation, a feed cup at the end of each shaft, spring means for normally urging the peripheries of said cups into engagement, the outer of said shafts being pivotally supported and arranged to have its axis tilted to carry its feed cup away from the other, a puller member cooperating with the cup of the outer shaft, a spring urged arm pivotally mounted within said outer cup, said arm carrying said puller member, treadle operated means connected with said outer shaft for rocking the same to carry the associated cup away from the other cup, and means connecting said treadle operated means with said arm to shift said puller member away from the cup of said outer shaft.

10. In a cup feed sewing machine having a frame, a pair of normally parallel shafts carried by said frame in inner and outer relation, a feed cup at the end of each shaft, spring means for normally urging the peripheries of said cups into engagement, one of said shafts being pivotally supported and arranged to have its axis tilted to carry its feed cup away from the other, a puller member cooperating with the cup of said one shaft, a thread severing blade carried by said

puller member at a point adjacent the point of cooperation of said member with said cup, a spring-urged pivotally mounted arm carrying said puller member, and treadle operated means for rocking said pivotally supported shaft and said arm to separate said cups and to carry said puller member away from the associated cup.

11. In a cup feed sewing machine having a frame, a pair of normally parallel shafts carried by said frame in inner and outer relation, a feed cup at the end of each shaft, spring means for normally urging the peripheries of said cups into engagement, one of said shafts being pivotally supported and arranged to have its axis tilted to carry its feed cup away from the other, a puller member cooperating with the cup of said one shaft, said puller member having portions extending under and over the other of said cups, a spring-urged, pivotally mounted arm carrying said puller member, and treadle operated means for rocking said pivotally supported shaft and said arm to separate said cups and to carry said puller member away from the associated cup.

12. In a cup feed sewing machine having a main frame, a pair of feed cups adapted to engage and feed the work, means for supporting and driving said feed cups, means for yieldingly urging said cups together, said cups being separable to permit the introduction of work therebetween, a shiftable puller member urged yieldingly against the periphery of one of said feed cups, an arm pivotally carried by said frame for supporting said puller member, means including a flexible connecting member operable at will for moving said arm about its pivot to carry said puller member away from said one of said feed cups, and tubular means carried by said frame for retaining and guiding said flexible connecting member intermediate its ends.

13. In a cup feed sewing machine, a main frame having a vertical standard and a laterally extending overhanging arm, a pair of shafts suspended from said arm in inner and outer relation, cooperating feed cups secured to said shafts adjacent their lower ends, the outer of said shafts being shiftably supported to allow movement of the related feed cup away from the other of said cups, spring means normally urging said outer shaft in a direction to carry its cup against the other cup, means operable at will for shifting said outer shaft to separate said cups, a bracket secured to said standard and extending beneath the cup secured to the inner shaft, an arm pivotally mounted on said bracket, said arm extending to a point adjacent the cup on the outer shaft, a puller member carried by said arm and arranged to engage the periphery of said cup on the outer shaft, spring means for urging said member against said cup, and means responsive to the operation of said means operable at will for shifting said arm to carry said member away from said cup.
